UNITED STATES PATENT OFFICE.

WILHELM B. BRONANDER, OF MONTCLAIR, NEW JERSEY.

INTERNAL-COMBUSTION ENGINE.

Application filed July 13, 1921, Serial No. 484,370. Renewed September 25, 1925.

This invention relates to internal combustion engines and more particularly to engines of the heavy oil type.

One of the objects of the invention is to provide a multiple cylinder heavy oil engine of the two cycle type with simple inlet and exhaust controlling means so constructed and arranged as to effect the desired cycle of operation.

10 Another object of the invention is to provide a long stroke engine of the type specified without necessitating excessive crank eccentricity.

15 Another object of the invention is to provide improved air compressing mechanism for an internal combustion engine of the type specified and to operate this air compressing mechanism by power derived from the engine in such a manner as to furnish 20 the compressed air at the desired intervals in the cycle of operation of the engine.

Another object of the invention is to so 25 operatively connect air compressing mechanism to an internal combustion engine of the type specified as to provide compressed air for scavenging and for the explosive mixture.

Another object of the invention is to provide 30 a multiple unit internal combustion engine of the type described having its various units so constructed and arranged as to effectively coordinate the parts of the various units and to operate the parts in the desired sequence.

35 Further objects of the invention will appear from the following specification.

The objects above noted are attained by an engine having a plurality of pairs of cylinders provided with inlet and exhaust ports 40 and with pistons so connected to a crank shaft as to operate in the desired sequence to control the opening and closing of the ports. Air compressing means is also connected with the piston operating connections, in such a manner that the compressed air is furnished to the respective cylinders through their inlet ports at the desired intervals, for scavenging the cylinders and for forming the combustible mixture. Oil is injected 50 into the cylinders at or near the completion of the compression stroke.

Certain embodiments of the invention have been illustrated in the accompanying drawings, in which,

55 Figure 1 is a longitudinal section of an internal combustion engine constructed in

accordance with my invention, the section being taken substantially on line 1—1 of Figure 3.

Figure 2 is a longitudinal section of a modified form of internal combustion engine, also embodying my invention.

Figure 3 is a top plan view of the engine shown in Figure 1.

Figure 4 is a longitudinal sectional view of another form of internal combustion engine constructed in accordance with my invention, and

Figure 5 is a plan view of a multiple unit engine of the form shown in Figure 4.

Referring first to the embodiment of the invention shown in Figures 1 and 3, the engine comprises a base 10 supporting in bearings 11—11 a crank shaft 12. The shaft 12 as shown in Figure 3 has two sets of 75 crank pins 13—13 and 14—14, the outer crank pins 13—13 being of like angularity and eccentricity and the inner pins 14—14 being also of light angularity and eccentricity. The crank pins 13—13 are angularly separated 180 degrees from the pins 14—14.

The center portion of the base 10 supports two parallel cylinders 20 and 30 interconnected by openings 21 and 22.

Cylinder 20 has an inlet port 23 and an exhaust port 24 spaced from the inlet port and cylinder 30 has spaced inlet and exhaust ports 33 and 34 respectively and it will be noted that the inlet port 23 of the 90 cylinder 20 is disposed opposite the exhaust port 34 of the cylinder 30 and the ports 33 and 24 are also positioned opposite to each other. The ports 23 and 24 in the cylinder 20 are controlled respectively by pistons 25 and 26 and ports 33 and 34 by pistons 35 and 36.

Referring to Figure 1, it will be seen that the base 10 supports at its ends substantially in alignment with the cylinders 20 and 30, 100 two sets of cylinders 40, 50 and 60, 70, the cylinders in each of the two sets being inclined with respect to each other. Cylinders 40, 50 are connected by a closed combustion chamber 41 and the cylinders 60, 70 by a 105 similar chamber 61. Cylinder 40 has an inlet port 43 and cylinder 50 an exhaust port 54 and the cylinders 60 and 70 are provided respectively with an exhaust port 64 and an inlet port 73.

The inlet ports 23 and 43 are connected by an inlet manifold 45 and the exhaust

ports 34 and 54 by an exhaust manifold 85. Inlet ports 33 and 73 are also connected by a manifold 75 and exhaust ports 24 and 64 by manifold 65.

5 The ports 43 and 54 in cylinders 40 and 50 are controlled by pistons 46 and 56 and the ports 64 and 73 in cylinders 60 and 70 are controlled by pistons 66 and 76.

10 The operating connections between the pistons and crank shaft will now be described.

15 As shown in Figure 3, each of the crank pins 13 has connected thereto, a connecting rod 80, the opposite ends of these rods being connected by cross pin 81. The pin 81 is journaled in a pair of boxes 82 slidably mounted in slides or guideways 83 as shown in Figures 1 and 3. At substantially its center, the cross pin 81 has fixed thereon, a 20 cross arm 84 extending laterally from the cross pin. Viewing Figure 1, the upper end of the arm 84 has pivoted thereto, links 85' and 86, the opposite ends of the links being connected respectively to pistons 25 and 46. 25 Similarly, the lower end of the cross arm has pivoted thereto, links 87 and 88 connected respectively to pistons 36 and 56.

30 As shown in Figure 3, air compressors are mounted on the opposite sides of the two sets of end cylinders 40, 50 and 60, 70 respectively, and these compressors are preferably double-acting and are operated by piston rods 89 secured to the cross pin 81 at the opposite ends thereof. Pistons 90 are 35 mounted in compressor cylinders 91 and are reciprocated by the piston rods 89 which in turn are reciprocated by the motion of the crank pins and connecting rods 80. The particular construction of the air compressors is illustrated in detail in certain other 40 figures of the drawings and will be herein-after described. Conduits 92 connect the opposite ends of the cylinders 91 with the intake manifold 45.

45 The crank pins 14—14 are connected in a similar manner by connecting rods 100 to a cross pin 101 journaled in boxes 102 slidably mounted in guideways 103. Intermediate its ends, the cross pin 101 has fixed thereto, a cross arm 104, the upper end of this arm being connected by links 105 and 106 to pistons 26 and 66. The lower end of the cross arm is connected by links 107 and 108 to pistons 35 and 76. Piston rods 50 109 are connected to the ends of the cross pin 101 and at their opposite ends are secured to pistons 110. Pistons 110 are 55 reciprocably mounted in air compressor cylinders 111 mounted on the opposite sides of the cylinders 60, 70. Conduits 112 connect the opposite ends of the cylinders 111 with the intake manifold 75.

60 Oil injection openings 113 and 114 are provided in the cylinders 20, 30 at substantially the centers thereof, whereby oil may

be injected between the opposing pistons when the pistons are disposed substantially at their inner limits of movement. Oil injection openings 115 and 116 are also provided for admitting oil into the combustion chambers 41 and 61 of the end sides of cylinders. The cylinders in the engine illustrated in Figures 1 and 3 are preferably water-jacketed, as shown at 117.

65 The cranks and crank pins on the crank shaft and the connecting rods and cross arms are preferably so disposed and connected to the pistons by the links described, that the pistons controlling the exhaust ports will open the exhaust ports before the inlet ports are opened and will close the exhaust ports before the inlet ports are closed, thereby trapping the compressed air between the pistons or between the pistons and the closed combustion chambers.

70 As illustrated in Figure 1, the crank shaft is rotating in the direction of the arrows and the pistons in the end sets of cylinders are just approaching their limit of compression or the end of the compression stroke 75 and the pistons in the cylinders 20 and 30 are approaching the end of the explosion stroke. In the operation of the cycle illustrated the exhaust controlling pistons 26 and 36 are about to open the exhaust ports 24 and 34 and after these ports are open, the inlet ports 23 and 33 will be opened by their pistons 25 and 35. In each case the exhaust ports will lead the inlet ports in 80 opening and closing.

75 Referring to Figure 3, the operation of the air compressing mechanism will be clear and it will be seen that by reason of the double-acting pistons, compressed air will be furnished to the inlet manifolds upon 85 both strokes of the connecting rods or cross pins. This compressed air will be admitted to the cylinders 20 and 30 at one end of the stroke and to the cylinders 40 and 50 and 60, 70 at the other end of the stroke.

80 In Figure 2 another embodiment of the invention is illustrated, this form of the invention comprising two substantially parallel cylinders 120 and 130 connected intermediate their ends by openings 121 and 122.

85 Cylinder 120 has an inlet port 123 and an outlet port 124 and cylinder 130 has an inlet port 133 and an outlet port 134. Pistons 125 and 126 in the cylinder 120 control respectively the ports 123 and 124 and pistons 135 and 136 control ports 133 and 134 in cylinder 130.

90 The pistons 125 and 136 are connected by links 127 and 137 to a cross arm 140 fixed to a cross pin 141 mounted in a box 142 slidably carried by guideways 143. The cross pin 141 is secured to one end of a pair of connecting rods 144, the opposite ends of these rods being carried by crank pins 145 of a crank shaft 146.

Air compressing mechanism is mounted at each end of the base of the engine, the mechanism on the left hand end viewing Figure 2 comprising a cylinder 147 having a piston 148 reciprocably mounted therein and carried by a piston rod 148'. Check valves 149 and 150 are carried by the cylinder 147 at the ends thereof. A vent 151 is provided intermediate the ends of the cylinder and conduits 152 and 153 connect two ends of the cylinder with an intake manifold 154, the opposite end of this manifold being connected to the inlet opening 123 of cylinder 120.

The pistons 126 and 135 are connected in a similar manner to the crank shaft by means of links 157 and 167, the opposite ends of the links being connected to a cross arm 160. The cross arm 160 is secured to a cross pin 161 mounted in a box 162 slidably carried by guideways 163. The cross pin 161 is also connected to a pair of connecting rods 164, the opposite ends of these rods being carried by crank pins 165 on the crank shaft 146, the crank pins 145 and 165 being angularly separated 180 degrees. An air compressor cylinder 177 is mounted at the end of the machine opposite the cylinder 147 and a piston 178 reciprocates in the cylinder being connected to cross pin 161 or box 162 by piston rod 178'. The cylinder 177 is provided at its two ends with check valves 179 and 180 and intermediate its end the cylinder has an air vent 181. Conduits 182 and 183 communicate with intake manifold 184, the opposite end of which communicates with the inlet port 133 of the cylinder 130. The cylinders 120 and 130 are preferably water-jacketed as shown at 185. The construction shown in Figure 2 operates in a manner similar to that shown in Figures 1 and 3, and the operation may be briefly described as follows: With the crank pins 145 and 165 in the positions shown, the exhaust controlling pistons 126 and 136 are about to uncover the ports 124 and 134 for the expulsion of the burnt gases. It will be noted that the exhaust ports will open before the inlet ports 123 and 133 are uncovered by the pistons 125 and 135 and furthermore due to the link connections between the respective pistons and the ends of the cross arms 140 and 160, the exhaust ports will close before the inlet ports close. In this way a compressed air charge will be trapped in the cylinders to be further compressed on the compression stroke of the engine.

The pistons 148 and 178 of the air compressor 147 and 177 will be reciprocated upon each stroke of the engine and will deliver a charge of compressed air upon both strokes, this charge scavenging the cylinders as well as mixing with the oil injected into the cylinders to form the combustible mix-

ture. Oil injection openings are shown at 186 and 187 and any suitable timing and oil injecting mechanism may be employed to deliver the fuel at the desired intervals, preferably substantially at the completion 70 of the compression stroke of the pistons.

Another embodiment of the invention is shown in Figure 4, this construction being similar to that shown in Figure 2, but differing in that the cylinders arranged side 75 by side are not interconnected or do not intercommunicate and also differing in that these cylinders are not parallel to each other but are angular in formation, or in longitudinal section, and converge toward each 80 other at their ends. In view of the close similarity in the structure shown in Figure 4 and that shown in Figure 2 and already fully described, the same reference characters are used in both these figures to indicate 85 corresponding parts. Moreover, as the operation of the construction shown in Figure 4 is substantially the same as that shown in Figure 2 and already described, a detailed description of the operation of the engine 90 shown in Figure 4 is not deemed necessary.

In Figure 5 a multiple unit engine is illustrated, the separate units being constructed in the manner illustrated in the sectional view shown in Figure 4. In Figure 5, however, the units are all connected to the same crank shaft 200, the cranks being angularly separated in a manner to properly coordinate the various units. In the showing, the cranks of the successive units A, B and C 100 are illustrated as separated successively 120 degrees, that is, the cranks for the unit B are separated 120 degrees from those of the unit A and the cranks for the unit C are separated 120 degrees from the unit B, and the cranks for unit C are also separated angularly 120 degrees from those of unit A.

As shown in Figure 5, each unit is provided at its opposite ends with an air compressor, the compressors being double-acting, as 110 shown in Figures 2 and 4. In order to furnish the compressed air to the respective cylinders in the most efficient manner and at the desired periods in the operation of the respective units, the intake manifolds for 115 the various units are cross connected. Thus the unit A has its air compressors connected to the cylinders of the unit C. The unit B has its compressors connected to the cylinders of the unit A and the unit C has its compressors connected to the cylinders of the unit B. This interconnection of the air compressors of the various units must of course be worked out in coordination with the angular displacement of the respective cranks or 120 crank pins of the units.

By the cross connection of the units just described, air is compressed upon one-half of the stroke of one unit, for scavenging the cylinder of the adjacent unit when the ex- 130

haust port thereof is opened and upon one-half of the return stroke, air is compressed for the charge to be admitted upon the opening of the inlet port.

5 As the units shown in Figure 5 correspond in construction to the structure shown in Figure 4, corresponding reference characters have been used in the two figures to indicate like parts.

10 In order to make clear the operation of the multiple unit construction of Figure 5, arrows have been placed on these units to indicate the direction of movement of the connecting rods and piston operating connections.

15 The operation of each unit is substantially the same as that already described in connection with Figure 2, except that as pointed out in connection with Figure 4 the cylinders do not intercommunicate in the 20 manner shown in Figure 2.

25 As the operation of each of the various constructions has been described in connection with the description thereof, no further description of the operation is deemed necessary.

30 From the foregoing specification wherein several specific embodiments of my invention have been described, it will be seen that I have provided the construction of an internal combustion engine of the two cycle, heavy oil type, having simple and efficient inlet and exhaust controlling mechanism so constructed and arranged as to effect the desired cycle of operation. Furthermore, it 35 will be noted that the construction described provides air compressing mechanism so connected to the piston operating means as to furnish the compressed air at the desired intervals for scavenging and for the combustible mixture.

40 Although certain specific embodiments have been illustrated and described, it will be understood by those skilled in the art that the invention is capable of further modification and that changes in the construction and arrangement of the various cooperating parts may be made without departing from the spirit or scope of the invention as expressed in the following claims.

45 50 What I claim is:

1. An internal combustion engine comprising a pair of cylinders disposed side by side, inlet and exhaust ports in each cylinder, a pair of pistons in each cylinder adapted to control said ports, a crank shaft, a pair of angularly disposed crank pins thereon, a connecting rod connected to one crank pin and to two of said pistons and a connecting rod connected on the other crank pin and the other two pistons, said connections being arranged to cause the exhaust ports in both cylinders to open in advance of the inlet ports and to close before the inlet ports.

55 60 65 2. An internal combustion engine comprising a pair of cylinders disposed side by side,

inlet and exhaust ports in each cylinder, a pair of pistons in each cylinder adapted to control said ports, a crank shaft, a pair of angularly disposed crank pins thereon, a connecting rod connected to one crank pin and to two of said pistons and a connecting rod connected to the other crank pin and the other two pistons, said connections being arranged to cause said pistons to move out of step to open and close said ports in the desired sequence.

70 75 80 85 3. An internal combustion engine comprising a pair of cylinders disposed side by side, inlet and exhaust ports in each cylinder, the inlet port of one cylinder being opposite the exhaust port of the other cylinder, a pair of pistons in each cylinder adapted to control said ports, a crank shaft, a pair of angularly disposed crank pins thereon, a connecting rod connected to one crank pin and to two of said pistons and a connecting rod connected to the other crank pin and the other two pistons, said connections being arranged to cause the exhaust ports in both cylinders to open in advance of the inlet ports and to close before the inlet ports.

90 95 100 105 4. An internal combustion engine comprising a pair of cylinders disposed side by side, inlet and exhaust ports in each cylinder, a pair of pistons in each cylinder adapted to control said ports, a crank shaft, a pair of angularly disposed crank pins thereon, a connecting rod connected to each crank pin and having its ends connected to a piston in each cylinder to cause said pistons to move out of step to open and close said ports in the desired sequence.

110 115 120 125 5. An internal combustion engine comprising a pair of intercommunicating cylinders disposed side by side, inlet and exhaust ports in each cylinder, a pair of pistons in each cylinder adapted to control said ports, a crank shaft, a pair of angularly disposed crank pins thereon, a connecting rod connected to one crank pin and to two of said pistons and a connecting rod connected on the other crank pin and the other two pistons, said connections being arranged to cause the exhaust ports in both cylinders to open in advance of the inlet ports and to close before the inlet ports.

130 135 140 145 6. An internal combustion engine comprising a pair of cylinders arranged side by side, spaced intake and exhaust ports in each cylinder, oppositely acting pistons in said cylinders, a crank shaft and common means connecting said crank shaft to the inlet controlling piston of one cylinder and the exhaust controlling piston of the adjacent cylinder.

150 155 160 165 7. An internal combustion engine comprising a pair of cylinders arranged side by side, spaced intake and exhaust ports in each cylinder, the inlet port in one cylinder being disposed opposite the exhaust port of the ad-

jacent cylinder, oppositely acting pistons in said cylinders, a crank shaft and common means connecting said crank shaft to the inlet controlling piston of one cylinder and the exhaust controlling piston of the adjacent cylinder.

8. An internal combustion engine comprising a pair of intercommunicating cylinders arranged side by side, spaced intake and exhaust ports in each cylinder, oppositely acting pistons in said cylinders, a crank shaft and common means connecting said crank shaft to the inlet controlling piston of one cylinder and the exhaust controlling piston of the adjacent cylinder.

9. An internal combustion engine comprising a pair of intercommunicating cylinders arranged side by side, spaced intake and exhaust ports in each cylinder, oppositely acting pistons in said cylinders, a crank shaft and common means connecting said crank shaft to the inlet controlling piston of one cylinder and the exhaust controlling piston of the adjacent cylinder to cause the exhaust ports in both cylinders to open in advance of the inlet ports and to close before the inlet ports.

10. An internal combustion engine comprising a pair of cylinders arranged side by side, intake and exhaust ports in said cylinders, pistons in said cylinders controlling said ports, a crank shaft, operative connections between said pistons and said crank shaft, air compressing mechanism communicating with said cylinders for furnishing compressed air thereto, and connections between the piston operative connections and the air compressing mechanism.

11. An internal combustion engine comprising a pair of intercommunicating cylinders arranged side by side, intake and exhaust ports in said cylinders, pistons in said cylinders controlling said ports, a crank shaft, operative connections between said pistons and said crank shaft, air compressing mechanism communicating with said cylinders for furnishing compressed air thereto, and connections between the piston operative connections and the air compressing mechanism.

12. An internal combustion engine comprising a pair of cylinders arranged side by side, intake and exhaust ports in said cylinders, pistons in said cylinders controlling said ports, a pair of crank pins, connecting rods carried by said pins and operatively connected to said pistons, air compressing mechanism communicating with the inlet ports of said cylinders, and means connecting said air compressing mechanism to said connecting rods.

13. An internal combustion engine comprising a pair of cylinders disposed side by side, inlet and exhaust ports in each cylinder, a pair of pistons in each cylinder adapt-

ed to control said ports, a crank shaft, a pair of angularly disposed crank pins thereon, a connecting rod connected to one crank pin and to two of said pistons and a connecting rod connected on the other crank pin 70 and the other two pistons, said connections being arranged to cause the exhaust ports in both cylinders to open in advance of the inlet ports and to close before the inlet ports, a pair of air compressing mechanisms 75 communicating with the inlet ports of said cylinders and operative connections between one of the connecting rods and one of the air compressing mechanisms and between the other connecting rod and the other air 80 compressing mechanism.

14. An internal combustion engine comprising a pair of interconnecting cylinders, an inlet port in one cylinder and an exhaust port in the other cylinder, a piston for controlling each of said ports, a crank shaft, operative connections including a connecting rod between the crank shaft and pistons, a double-acting air compressor communicating with the inlet port, and operative connections between the connecting rod and the air 90 compressor.

15. An internal combustion engine comprising a pair of cylinders arranged side by side, inlet and exhaust ports in each cylinder, a piston for controlling each of said ports, a crank shaft, crank pins thereon, a connecting rod carried by each crank pin, the other ends of said rods being mounted for reciprocatory motion, operative connections between the connecting rods and pistons, a double-acting air compressor and operative connections between said air compressor and one of the connecting rods. 95 100

16. An internal combustion engine comprising a pair of cylinders arranged side by side, inlet and exhaust ports in each cylinder, a piston for controlling each of said ports, a crank shaft, crank pins thereon, a connecting rod carried by each crank pin, the other ends of said rods being mounted for reciprocatory motion, an air compressor for furnishing compressed air to said cylinders and including a piston, and operative connections between the air compressor piston and one of the connecting rods. 105 110 115

17. An internal combustion engine comprising a pair of cylinders arranged side by side, inlet and exhaust ports in each cylinder, a piston for controlling each of said ports, a crank shaft, crank pins thereon, a connecting rod carried by each crank pin, the other ends of said rods being mounted for reciprocatory motion, operative connections between the connecting rods and pistons, a pair of air compressors communicating with the inlet ports of each cylinder, and operative connections between the connecting rods and the air compressors. 120 125

18. An internal combustion engine com-

- prising a pair of cylinders arranged side by side, inlet and exhaust ports in each cylinder, a pair of intercommunicating cylinders arranged in substantial alinement with the first named pair of cylinders at each end of said pair, an inlet port in one cylinder of each of the intercommunicating pairs and an exhaust port in the other cylinder of each pair, a pair of pistons in each cylinder of the first named pair for controlling the ports therein and a piston in each of the cylinders of the last named pairs, a crank shaft and operative connections between said shaft and said pistons to control the opening and closing of the inlet and exhaust ports in the desired sequence.
19. An internal combustion engine comprising a pair of cylinders arranged side by side, inlet and exhaust ports in each cylinder, a pair of intercommunicating cylinders arranged in substantial alinement with the first named pair of cylinders at each end of said pair, an inlet port in one cylinder of each of the intercommunicating pairs and an exhaust port in the other cylinder of each pair, a pair of pistons in each cylinder of the first named pair for controlling the ports therein and a piston in each of the cylinders of the last named pairs, a crank shaft, a pair of angularly separated crank pins on said shaft, a connecting rod on each pin and having a cross arm secured thereto and links connecting the exhaust port controlling pistons of the two intercommunicating cylinders to one end of each cross arm and links connecting the other end of each cross arm to the inlet controlling pistons of said two cylinders.
20. An internal combustion engine comprising a pair of cylinders arranged side by side, inlet and exhaust ports in each cylinder, a pair of intercommunicating cylinders arranged in substantial alinement with the first named pair of cylinders at each end of said pair, an inlet port in one cylinder of each of the intercommunicating pairs and an exhaust port in the other cylinder of each pair, a pair of pistons in each cylinder of the first named pair for controlling the ports therein and a piston in each of the cylinders of the last named pairs, a crank shaft, a pair of angularly separated crank pins on said shaft, a connecting rod on each pin and having a cross arm secured thereto and links connecting the exhaust port controlling pistons of the two intercommunicating cylinders to one end of each cross arm and links connecting the other end of each cross arm to the inlet controlling pistons of said two cylinders.
21. An internal combustion engine comprising a pair of intercommunicating cylinders arranged side by side, an inlet port in one cylinder and an exhaust port in the other cylinder, pistons controlling said ports, a pair of intercommunicating cylinders arranged in substantial alinement with the first mentioned cylinders and at each end thereof, an inlet port in one cylinder of each of said pairs, and an exhaust port in the other cylinder of each pair, a piston in each cylinder of each of the last mentioned pairs, a crank shaft, angularly separated crank pins thereon, a connecting rod carried by each pin, a cross arm secured to the free end of each connecting rod, links connecting one end of each cross arm to the exhaust port controlling pistons of said cylinders and the other end of each cross arm with the inlet controlling pistons of the cylinders.
22. An internal combustion engine comprising a pair of cylinders disposed side by side and angular in longitudinal section, the ends of the adjacent cylinders converging, inlet and exhaust ports in each cylinder, pistons controlling said ports, a crank shaft, crank pins thereon, a pair of connecting rods carried by said pins, and means connecting the free ends of said connecting rods to the pistons in the adjacent cylinders in a manner whereby the exhaust ports will open before the inlet ports open and the exhaust ports will close before the inlet ports close.
23. An internal combustion engine comprising a pair of cylinders disposed side by side and angular in longitudinal section, the ends of the adjacent cylinders converging, inlet and exhaust ports in each cylinder, pistons controlling said ports, a crank shaft, crank pins thereon, a pair of connecting rods carried by said pins, and means connecting the free ends of said connecting rods to the pistons in the adjacent cylinders in a manner whereby the exhaust ports will open before the inlet ports open and the exhaust ports will close before the inlet ports close, a pair of air compressing mechanisms communicating with the inlet ports and means for connecting each of said mechanisms with one of said connecting rods in a manner whereby the compressed air will be discharged to the inlet ports at the desired intervals in the cycle of operation of the engine.
24. A multiple unit internal combustion engine comprising a crank shaft, a plurality of units arranged side by side and coupled to said shaft at predetermined angles about the axis thereof, inlet and exhaust ports in each unit, double-acting air compressing mechanism operatively connected to each unit and connected to the inlet port of the next succeeding unit.

25. A multiple unit internal combustion engine comprising a crank shaft, a plurality of units arranged side by side and coupled to said shaft at predetermined angles about the axis thereof, inlet and exhaust ports in each unit, double-acting air compressing mechanism operatively connected to each unit and connected to the inlet port of the next succeeding unit in the 10 direction of rotation of the crank shaft.
26. A multiple unit internal combustion engine comprising a crank shaft, a plurality of units arranged side by side and coupled to said shaft at predetermined angles about 15 the axis thereof, inlet and exhaust ports in each unit, double-acting air compressing mechanism operatively connected to each unit and connected to the inlet port of the next succeeding unit and an intake manifold 20 connecting the air compressing mechanism of each unit to the inlet port of the next succeeding unit.
27. A multiple unit internal combustion engine comprising a crank shaft, a plurality of units arranged side by side coupled to said shaft at predetermined angles about the axis thereof, each unit comprising a plurality of cylinders, inlet and exhaust ports in each cylinder, double-acting air 25 compressing mechanisms operatively connected to each unit, and manifolds connecting the air compressing mechanisms of each unit to the inlet ports of the next succeeding unit.
28. An internal combustion engine comprising a pair of cylinders disposed side by side and angular in longitudinal section, the ends of the adjacent cylinders converging, inlet and exhaust ports in each cylinder, pistons controlling said ports, a crank shaft extending between said cylinders, crank pins thereon, a pair of connecting rods carried by said pins, and means connecting the free 35 ends of said connecting rods to the pistons in the adjacent cylinders in a manner whereby the exhaust ports will open before the inlet ports open and the exhaust ports will close before the inlet ports close.
29. An internal combustion engine comprising a pair of cylinders, a pair of oppositely movable pistons in each cylinder, intake and exhaust ports in each cylinder, a double-acting air compressor communicating with the intake port of each cylinder, a crank shaft, operative connections between 40 said shaft and said pistons and operative connections between said shaft and said air compressors.
30. An internal combustion engine comprising a pair of cylinders arranged side 45 by side, a pair of pistons in each cylinder, intake and exhaust ports in each cylinder, a double-acting air compressor communicating with the intake port of each cylinder, a crank shaft, operative connections between 50 said shaft and said pistons and operative connections between said shaft and said air compressors.
31. An internal combustion engine comprising a pair of cylinders, a pair of pistons 55 in each cylinder, intake and exhaust ports in each cylinder, a crank shaft, operative connections between said shaft and said pistons and means operatively connected to said crank shaft and communicating with the intake ports of said cylinders for supplying compressed air to said cylinders upon each 60 stroke of the pistons.
32. An internal combustion engine comprising a pair of cylinders arranged side by 65 side, a pair of oppositely movable pistons in each cylinder, intake and exhaust ports in each cylinder, a crank shaft, operative connections between said shaft and said pistons and means operatively connected to said 70 crank shaft and communicating with the intake ports of said cylinders for supplying compressed air to said cylinders upon each stroke of the pistons.

In witness whereof, I have hereunto set 75
my hand this 12th day of June, 1921.

WILHELM B. BRONANDER.
